UNITED STATES PATENT OFFICE.

ABEL H. FROST AND FRED L. BRYANT, OF CHICAGO, ILLINOIS, ASSIGNEES
TO AMES & FROST, OF SAME PLACE.

MACHINE FOR ATTACHING FABRICS TO BED-BOTTOM FRAMES.

SPECIFICATION forming part of Letters Patent No. 319,476, dated June 9, 1885.

Application filed April 6, 1883. (No model.)

To all whom it may concern:

Be it known that we, ABEL H. FROST and FRED L. BRYANT, of Chicago, in the county of Cook and State of Illinois, have invented 5 certain new and useful Improvements in Machines for Attaching Fabrics to Bed-Bottom Frames; and we do hereby declare that the following is a full, clear, and exact description thereof, reference being had to the accompanying drawings, and to the letters of reference marked thereon, which form a part of this specification.

This invention relates to the manufacture of that class of bed-bottoms known as "woven-wire mattresses," in which a coiled wire fabric is secured to the end bars of a suitable frame, by which frame the desired support and tension are given to the fabric.

The invention relates to means for connecting the fabric to the end bars; and it has for its object to provide a machine to facilitate and improve this part of the manufacture, heretofore performed essentially by hand.

The form of union of the fabric with the 25 end bars of the frame contemplated by our invention, and herein illustrated as being made by the machine, is one in which the fabric is forced into a longitudinal groove in the end bar and therein held by a tongue inserted and 30 secured in said groove over the fabric.

The machine contains devices for forcibly inserting the fabric and tongue into the grooved end bar for facilitating the nailing of the strip while held in this position by the 35 pressing devices, means by which the bed-bottom may be turned end for end in the machine for fastening the opposite extremities of the fabric to the end bars, and sundry other mechanisms designed to favor the accomplishment of the work of attaching the fabric 40 speedily and skillfully.

The features claimed to contain invention will be hereinafter more fully set forth, and designated in the appended claims.

In the drawings, Figure 1 is a perspective view of the machine wanting the gear mechanism by which it is driven. Fig. 2 is an end view at the head of the machine. Fig. 3 is a transverse vertical section in the line $x-x$ of 45 Fig. 4, looking in the direction of the arrow a . Fig. 4 is a central vertical section in the line $x-x$ of Fig. 2, looking in the direction of

the arrow a' . Fig. 4^a is a fragmentary view in vertical section transverse to the presser-beam, or in the line $y-y$ of Fig. 2, looking in 55 the direction of the arrow a^2 . Fig. 5 is a fragmentary plan view of the movable bed upon which the fabric and end beam are supported preparatory to the further operation of the machine. Fig. 6 is a perspective view of the 60 end of the bed shown in Fig. 5. Fig. 7 is a removable support for the tongued strip to be applied to the grooved end bar. Fig. 7^a is a transverse section of the support shown in Fig. 7. Fig. 8 shows the end beam after 65 the fabric has been attached. Fig. 9 is a transverse vertical detail section of the beam and plates to which the toggle-arms are connected through the axis of their connection. Fig. 10 is a detail plan showing the crank for 70 operating the toggle-arms. Figs. 11 and 12 are views of the casters which uphold the table.

A A are frame-uprights. A' A' are horizontal side beams, and A² A² are cross frame-beams having their upper faces at about half 75 the height of the frame.

A³ is a deep and rigid cross-beam located at one end of the machine and secured to the outer faces of the adjacent uprights A A. So The upper edge or face of said beam A³ is straight and on a level with the corresponding edges of the side beams, A'. Said beam A³ is the stationary one of two jaws between which the parts to be joined are compressed. 85 The opposing or movable jaw may be mounted, guided, and operated by any suitable or convenient devices. As here shown, said movable jaw consists of a beam, B, supported directly over the beam A³, and in the same plane therewith, by means of rods B², connected with the ends of the latter and with the ends of a similar or suitable beam, B', also located in the same plane with the bed-beam A³, and beneath the latter, as plainly indicated in Figs. 95 1 and 4.

The vertically-movable parts described are held in their proper plane of movement by guides consisting, in the present instance, of bars a⁴, affixed to the front face of the beam A³, and parallel with the vertical faces of the adjacent frame-uprights A', aided by the brackets b, attached to the upper part of the frame and apertured to give passage to the 100

rods B². The beam B' slides up and down between the bars a⁴ and the adjacent uprights, and the rods B² slide in said brackets b.

B³ B⁴ are castings attached to the ends of the 5 beams B and B', respectively, as shown, for the purpose of giving suitable connection for the rods B² and for the truss rods b', when the latter are applied to said beams.

Any approved mechanism may be employed 10 to give the desired vertical movement and power to the presser-beam B. For this purpose the drawings show two pairs of equal toggle-arms, C C, pivoted to each other at c and to the adjacent beams A³ and B' at c², and operated by 15 means of a crank, c³, on the shaft D. To secure the necessary power in a hand-machine, said shaft may be driven by a train of gear-wheels affixed to similarly-mounted and parallel shafts, as indicated in Figs. 2, 3, and 4, 20 wherein the last shaft of the series is shown as being provided with a hand-wheel, D⁵.

C' C' are connecting rods which join the hinged points of the toggle-arms with the crank-pin c³ of said shaft D. By these or 25 equivalent devices the parallel beams B and B' may be depressed or raised at pleasure, and any desired compressive force may be imparted to the presser-beam B, working in opposition to the stationary beam A³.

30 In the application of the toggle-arms C C to the beams A³ and B' angle-castings C² C², Figs. 2 and 9, are applied to opposite faces of the said beams, being formed with flanges c' on their outer faces, against which the ends of 35 the toggle-arms may bear, so as to relieve the strain that would otherwise fall upon the pivot-bolts c². It will be observed that the plates C² extend some distance inwardly from the margins of the beams to which they are 40 applied, from which it will be apparent that in a machine of convenient height, wherein the beams A³ and B' are of considerable depth, longer toggle-arms may be used than would be practicable were the latter pivoted at or 45 upon the adjacent faces of said beams.

In the operation of the machine the end bar of the bed-frame (marked G in the several figures of the drawings) is supported by the stationary beam A³, with the groove thereof 50 in line with the presser-beam B, and with the fabric placed over the groove. The tongue-bearing strip or cleat which is to secure the fabric is then forced to its place by the descent of the presser-beam B.

55 To facilitate the manipulation of the parts to be joined, a movable table is provided for the immediate support of the fabric and end bar together, with stops therefor, and devices for holding the fabric and end bar in proper relation with each other until fastened. Mechanism is also provided for temporarily attaching the tongued strip to the lower face of the presser-beam B, whereby the tongue upon 60 said strip will accurately enter the groove in the end bar when the presser is brought down.

65 F is the removable table referred to for the support of the fabric. Said table is of con-

venient length to allow the fabric to lie smoothly extended thereon without tension, and rests otherwise free of the frame upon 70 four or other suitable number of upturned casters, E', attached to cross-pieces E of the frame. At a central point of the table, and on its under side, it is provided with a cylindric vertically-dependin pin, F', which extends into 75 a slot formed by two parallel bars, e, secured longitudinally of the machine to the cross-bars E, as shown in Figs. 3 and 4. The table is thus adapted to rotate horizontally on the pin F' as its axis, and also to be moved back and 80 forth longitudinally of the machine, or to and from the presser-beams B and A³, and to facilitate these several movements pins or handles f' are provided in the sides of the table. At each end of the table a projecting metal plate, F², 85 is secured thereto flush with the bottom of said table and of proper width to receive and support the end bar, G, to which the fabric H is to be secured. The adjacent end of the table is made of thickness or height about equal to 90 the thickness of the end bar. In the present instance this is done by the addition of a beveled cross-strip, f'. Across the end of the table is also secured a metal strip, F³, provided with a series of holes, f², intended to 95 receive pins f³, by which the fabric may be held laterally extended to equal or proximate in width the length of the end bar. If the end bar, G, is provided with the metal plates g² on its lower surface (by which it is to be attached to the side bars of the bed-frame) before the fabric is secured thereto, a removable board, G', having recesses g³ to receive the plates g², is employed, to be placed on the plate F², and to immediately support the end bar, G, 105 in order to hold the latter straight while subject to pressure from the beam B.

In the use of the machine for bed-frames of different widths, a series of recesses, g³, will be made in the board G', as shown, and several such boards of unequal thickness may be advantageously provided for different thicknesses of end bars. The fabric being placed on the table F, and the end bar, G, with its groove uppermost upon the plate F², the fabric is adjusted with its end overlying the groove g of the end bar, and is laterally stretched to the proper width and then secured in this position by the pins f³, thrust through the fabric near the margin thereof into the holes f². The parts being thus arranged, the table is so moved as to bring the plate F² over the cross-beam A³ and in place for the end bar to receive the strip S. A stop, F⁴, and stops a³, attached to the vertical face of the beam A³, 115 serve to arrest the table and to hold the end bar in place. Any other suitable form of stops may obviously be employed for the same purpose.

For the purpose of temporarily attaching the tongue-bearing wooden strip S to the lower face of the presser-beam B with such accuracy as to insure the entrance of the tongue s thereon into the groove g of the end bar, a

removable plate, J, is provided on the said lower face of the presser-beam B, being longitudinally grooved to conform with the shape of the upper surface of the strip. Through 5 or from this plate short sharp pins *j*, Fig. 4, project downwardly, so that when the presser-beam is brought down upon a strip the pins *j* enter the latter and lift and support the same until forcibly removed. For the proper use 10 of this device a removable table, S', is provided, Figs. 7 and 7^a, having legs or uprights S^a, which may rest on the beam A^a, and projections s^a, by which its position on said beam will be readily gaged. Preparatory to placing 15 a strip this table S' is set upon the bed A^a, and a strip is laid thereon with its tongue *s* in the groove *s'*, made to correspond with that of the end bars. The presser-beam is then brought down upon the strip, and upon being 20 raised lifts the strip by the pins *j*, as above described. When thereafter the end bar and fabric are brought into position over the bed-beam A^a, the strip S is thus perfectly adjusted to unite therewith by simply depressing the 25 beam B.

The removable plate J may be attached to the beam B by any suitable means; but, as here shown, it is provided with transverse dovetailed grooves *j'*, Fig. 2, which fit corresponding 30 transverse tongues, *j*², on the beam. A separate plate, J', having these tongues attached, and being itself screwed or bolted to the beam, may be advantageously employed.

In order to prevent the fabric from being 35 drawn out of place at one or more points of its width when forced into the groove of the end bar, an automatic spring presser-bar, I, is provided, being arranged in position to bear upon the fabric opposite the plate F^a, 40 and being contrived to strike the fabric and engage the same, so as to hold it in place, before the tongue of the strip S has entered the groove of the end bar. This presser-bar I is mounted on vertical rods *i*, which, as here indicated, 45 are secured to the lugs *i'* on the castings B^a, and slide freely through the presser-bar I, the desired downward pressure upon the fabric being given by means of the expanding springs I', surrounding said rods *i*.

50 For the purpose of fastening the strip S permanently in place after being firmly pressed down upon the end bar and fabric, a series of vertical tubes, b^a, Figs. 2 and 4^a, are provided in the presser-beam B, directly over the strip, 55 intended to admit nails b², Fig. 4^a, which may be dropped therein, and driven by means of a rod and hammer. Said tubes may extend through the plates J' and J, or they may simply coincide with apertures in said plates.

60 Instead of using a separate rod and hammer, a second presser-bar provided with a series of rods arranged to enter the tubes may obviously be contrived to force the nails home simultaneously.

65 The groove *g* of the end bar is preferably of the peculiar shape indicated in Figs. 4^a and 8 of the drawings—that is to say, having

the lateral extension *g'* on that side remote from the body of the fabric. The strip S is constructed to overlie the end bar and fabric 70 on both sides of the groove *g*, and to also extend beyond the groove-extension *g'* just mentioned. The tongue *s* does not fill the said extension *g'*, but only the main groove *g*, wherefore a space is left at *g'* after the strip S is 75 forced home. In this space the ends of the fabric coils are intended to lie unflattened or only partly flattened, so that when tension is applied to the fabric in attaching the end bars to the side bars of the bed-bottom and in the 80 subsequent use of the bed-bottom said wires are less liable to be drawn out from beneath the tongued fastening-strip S.

In the use of the machine described such force is usually and desirably employed as 85 will not only flatten the fabric coils between the opposed surfaces of the strip and end bar, but will compress the wires into the said surfaces and thus make a bug-proof joint. If preferred, a body of putty may be inserted 90 in the groove-extension *g'* prior to applying the fabric and strip; but if the latter is properly forced down into contact with the end bar it will usually be sufficient to merely stop the ends of this space with putty after the 95 parts are joined.

In the mechanism shown for operating the presser-beam B the two pairs of toggle-arms C throw in the same direction, which is calculated to give an end-thrust to the beam B'. 100 To counteract this effect a rod, c^a, is pivoted to said beam, near one end thereof, and to the bar a^a at the other end of said beam. By using a double crank in place of the single crank c^a on the shaft D, one for each or each pair of 105 the connecting-rods C', the toggle-arms would be thrown in opposite directions and the end-thrust thus obviated, so that the rod c^a could be omitted. The particular devices for operating the presser-beam are not, however, material to the general invention. 110

If in place of the straight rods B² curved or offset connections of proper strength are employed to join the beams B and B', room may be afforded for swinging the table F so 115 as to carry the end bar into place between the beams by a rotary movement only of said table, and in that case its longitudinal movement, obtained by means of the slot between parallel bars e, may be dispensed with, some 120 one of many familiar forms of stops being provided to arrest the table in exact position other than those shown; so, also, in place of the pins *j*, for picking up the strip S and holding it in a proper position to meet the grooved 125 end bar, other and obvious means may be employed to insure the proper relation between the end bar and strip at the moment pressure is applied to them.

For convenience, the temporary strip support S' is usually disposed of when not in use by placing it upon brackets projecting from the face of the beam A^a a few inches below its upper edge, from which it is lifted to place 130

on said beam when required with but little delay. If desired, said strip support may be hinged to the said front face of the beam A³ by the lower ends of the gage-arms s³, in which case it may be swung up and down into and out of place with even greater expedition.

In securing woven-wire fabric within grooves in the end rails of bed-bottom frames, it has heretofore been the practice to first bend the fabric into the groove and to then insert the tongue, subsequently nailing or otherwise fastening the tongue in place. This method has the objection that when tension is finally applied to the fabric and in the use of the bed the wires of the fabric are drawn gradually into the wood of the tongue, and thus lessen the tension on the bed-bottom. In the method herein set forth, wherein the fabric is placed over the groove and is forcibly carried into it by pressure upon the tongue, the great strain upon the fabric wires beneath the tongue serves to embed them in the latter and into the adjacent walls of the groove, so that subsequent tension of the fabric produces no further indentation of the wood, and slackening of the tension from such indentation is avoided. This method herein set forth forms the subject of a separate application for patent, Serial No. 184,277, filed by us in the United States Patent Office June 9, 1884.

The bed-bottom having features of construction herein shown will form the subject of a separate application for patent.

We claim as our invention—

1. In a machine for fastening fabric to the end bars of bed-bottoms, the combination, with a rest for the end bar, and a table for the support of the extended fabric, of a horizontally-movable presser-beam, and mechanism for operating the same, substantially as described.
2. The combination, with opposing presser-beams A³ B, of a movable table for the support of the fabric and end bar in proper relation to each other, substantially as described.
3. The combination, with opposing presser-beams, of a rotating and longitudinally-movable table for the support and movement of the fabric and end bar, substantially as described.
4. The combination, with opposing presser-beams, of a table for the support of the fabric practically flush with the end bar, and means for holding the fabric properly extended, substantially as described.
5. The combination, with a support for the end bar, of an adjacent support for the fabric, having holes f², and being about flush with the upper surface of the end bar, and pins f³, substantially as described, and for the purposes set forth.
6. The combination, with the opposing presser-beams and an adjacent support for the fabric, of an auxiliary spring-presser, I, for holding the fabric, substantially as described.
7. The combination, with the opposing presser-beams, of a rotating table, F, provided with plates F² for the end bars at its opposite ends, substantially as described.

8. In combination with the opposing presser-beams, the table F, a central pin, F', a part or parts forming a slot for said pin, and suitable supports for the table, substantially as described.

9. In combination with the opposing presser-beams, rotary table F, provided with a center pin, F', caster-wheels E', for the support of the table, substantially as described.

10. In combination with the rotary and longitudinally-movable table and the presser-beams, a stop or stops for arresting the table in position to bring the cross-bar thereon into place between the presser-beams, substantially as described.

11. In combination with the opposing presser-beams, and means for fixing the position of the end bar, the beam B, together with means for attaching the strip S thereto, and means for gaging the position of the strip when being so attached, substantially as described.

12. In combination with the opposing presser-beam, the beam B, having its face shaped to conform with the outer surface of the cleat S, substantially as described.

13. In combination with the beam B, the points j in its lower surface, constructed to enter the cleat and to sustain the same, substantially as described.

14. In combination with the movable presser-beam B, the removable plate J, and points j, substantially as described.

15. In combination with the opposing presser-beams, the transversely-grooved board G, fitted to receive the irons attached to the cross-bar of the bed-frame, substantially as described.

16. In combination with the beam B, provided with means for seizing the cleat S, the grooved gage-board S', constructed to support the cleat in position corresponding with that which it is desired to have when borne against the end bar, substantially as described.

17. In combination with the stationary beam A³ and connected movable beam B and B', arranged as shown, the toggle-arms C C, pivoted to the beams B' and A³, the shaft D, having crank c³, and the connecting-bars C' C', together with means for rotating the shaft D, substantially as described.

18. In combination with the beams A³ and B' and toggle-arms C C, the angle-irons C², provided with flanges c², and the pivot-bolts c², substantially as described.

In testimony that we claim the foregoing as our joint invention we affix our signatures in presence of two witnesses.
